(57) **CLAIM**

The ornamental design for a fastener, as shown and described.

DESCRIPTION

FIG. 1 is a top, front, left isometric view of a fastener; FIG. 2 is a left side elevation view of the fastener of FIG. 1; FIG. 3 is a right side elevation view of the fastener of FIG. 1;

FIG. 4 is a rear elevation view of the fastener of FIG. 1; FIG. 5 is a front elevation view of the fastener of FIG. 1; FIG. 6 is a top plan view of the fastener of FIG. 1; and,

FIG. 7 is a bottom plan view of the fastener of FIG. 1. The dash-dash-dash broken lines in the drawings illustrate portions of the fastener and form no part of the claimed design. The dash-dot-dash broken lines in the drawings define the bounds of the claim and form no part thereof.
